UNITED STATES PATENT OFFICE.

THOMAS W. R. McCABE, OF WINSTED, CONNECTICUT, ASSIGNOR TO THE
WILLIAM L. GILBERT CLOCK COMPANY, OF SAME PLACE.

CLOCK-CASE.

SPECIFICATION forming part of Letters Patent No. 645,231, dated March 13, 1900.

Application filed June 15, 1899. Serial No. 720,635. (No model.)

To all whom it may concern:

Be it known that I, THOMAS W. R. McCABE, a citizen of the United States of America, residing at Winsted, in the county of Litchfield, 5 and State of Connecticut, have invented a certain new and useful Improvement in Clocks, of which the following is a description, reference being had to the accompanying drawings, wherein—

10 Figure 1 is a rear view of parts embodying the invention. Fig. 2 is a top view of the same parts from the position A. Fig. 3 is a view in section on the plane denoted by the dotted line x x , omitting the clockwork-frame and its supports. Fig. 4 is a face view of a portion 15 of the plate, hereinafter lettered b . Fig. 5 is a similar face view of substantially the same portion of plate b interlocked with a portion of the cylinder lettered d hereinafter, the view being an edge view so far as that cylinder is concerned. Fig. 6 is a side view of substantially the same portion of the cylinder d as is shown in Fig. 5.

The object of the improvement is the production of parts and mechanisms for attaching a clockwork-frame (carrying the clock-movement) to the dial and parts immediately supporting the dial in a novel manner, with resulting advantages.

30 In the accompanying drawings the letter a denotes the clockwork-frame as a whole. This frame carries the clock-movement, which movement is not shown in the drawings. The clockwork-frame is attached to and carried by the plate b through the medium of the posts c . The plate b has peripheral projections b' . It also has a locking-indentation b^2 . It also has springs b^3 struck from the material of the plate.

The letter d denotes a cylinder which may 40 properly and suitably be made of sheet metal. It is provided with certain bayonet-joint mortises d' , adapted for coöperation with the peripheral projections b' . By the coöperation of the two the plate b can be attached to and 45 detached from the cylinder d after the common bayonet-joint fashion. The cylinder d is provided with a tongue d^2 , struck from the material of the cylinder, which when the parts are in proper alinement is bent into the locking-indentation b^2 , a proceeding which locks the plate and cylinder firmly together.

The letter e denotes a dial-mat fast to the cylinder d . The letter f denotes the dial. These two parts, the dial-mat and the dial, 55 may be made in one piece, and such construction is within the purview of the claim, but the preferred construction is that they be separate.

The letter b^3 denotes springs struck from 60 the material of the plate b , which bear against the back of the dial and hold the parts against any loose motion with relation to each other.

I claim as my improvement—

In combination; the clockwork-frame; the 65 plate provided with the peripheral projections, with the peripheral locking-indentation and with the springs struck from the material of said plate; the cylinder provided with the bayonet-joint mortises and with the 70 tongue adapted to coöperate with said indentation; the dial-mat; and the dial, all substantially as described and for the purposes set forth.

THOMAS W. R. McCABE.
